WILLIAM THOMAS HATTEN, OF HAY CREEK, OREGON.

AX-HANDLE SHIELD AND FASTENING.

1,347,371.

Specification of Letters Patent. Patented July 20, 1920.

Application filed April 29, 1919. Serial No. 293,489.

To all whom it may concern:

Be it known that I, WILLIAM T. HATTEN, a citizen of the United States, residing at Hay Creek, in the county of Jefferson and

5 State of Oregon, have invented a new and useful Ax-Handle Shield and Fastening, of which the following is a specification.

This invention relates to ax handle shields and fastenings.

10 An object is to provide a shield or protector for the handles of axes or similar tools which will effectually guard against breaking the handle close to its connection with the head of the tool, whether in delivering a straight blow as when splitting a log of wood, or when subjecting the handle of the ax to a side strain, as when freeing the ax from the portions of a partially split log, said shield serving the additional function of fastening the handle to the ax head.

Another object is to provide a shield of this character which may be applied to either a single or double-edged ax without materially altering the construction of the 25 same, and which will not add any appreciable weight thereto, the same being constructed of sheet metal and of such simple formation as to be readily manufactured and applied to the ax or other tool of like 30 character without adding materially to the cost thereof.

A full and complete understanding of the invention may be obtained from a consideration of the following detailed description, 35 taken in connection with the accompanying drawing forming a part of this specification; it being understood that while the drawing shows a practical form of the invention, the latter is not confined to strict 40 conformity therewith, but may be changed or modified, so long as such changes or modifications mark no material departure from the salient features of the invention, as 45 specifically pointed out in the appended claims.

In the drawing, in which like reference characters designate similar parts throughout the several figures:

Figure 1 is a side elevation of a portion 50 of a two-edged or double-bitted ax having the invention applied thereto and with the handle broken away.

Fig. 2 is a transverse section, taken on the line 2—2 of Fig. 1.

55 Fig. 3 is a longitudinal section taken on the line 3—3 of Fig. 1.

Fig. 4 is a section taken on the line 4—4 of Fig. 3.

Fig. 5 is a detail perspective view of one of the shields.

60 Fig. 6 is a side elevation, parts being partly broken away, showing the invention applied to an ordinary single-edged ax.

Fig. 7 is an end view of the ax shown in Fig. 6.

65 The ax illustrated in Figs. 1 to 5 inclusive, of the drawing, is of the two-edge formation commonly known as a double-bitted ax, wherein the head proper 1 is provided with a cutting edge 2 at each end, and having at 70 the center thereof a longitudinally disposed opening or eye 3, preferably elliptical in cross section for the reception of the end of the handle 4 in the usual manner.

75 At a point midway of the cutting edges and arranged to intersect the longitudinal central line of the handle 4, the head 1 is provided with a transverse bore or aperture 5 passing through both sides of the head and adapted to receive a metal pin 6, for 80 the purpose of holding said head upon the end of the handle, and at the same time to engage with co-acting means carried by the shield of the present invention, in a manner to be explained.

85 The handle 4 is of ordinary wooden type formed in the usual manner and provided with a transversely disposed aperture 7 adapted to register with the aperture 5 in the head, when the same is in the position on the handle to receive the pin 6.

The opening or eye 3 of the head 1 is somewhat larger than that portion of the handle traversing the same, the difference in size being designed to accommodate a 95 pair of sheet metal plates 8—8, which are of sufficient thickness to cause a tight fit of the handle in the head and to prevent any relative movement of the two parts.

The plates 8—8 which are used in pairs 100 upon axes of the kind described, are formed U-shaped in cross section, to fit the thinner edges of the handle where entering the head, and are adapted to lie with their outer ends 9 flush with the outer end face of the head 1 105 and to extend, at their inner ends 10 a considerable distance beyond the inner end face of the head and along the edges of the handle in order to brace the same and to shield it from injury when contacting with 110 objects being split or chopped by the ax. These plates are seen to be set crosswise of

the plane of action of the tool, are of equal thickness throughout, and have their greatest width where set within the eye.

The inner ends 10 of the shields 8 converge somewhat to conform to the shape of the ordinary ax handle, and are provided at their opposed edges, near their outer ends, with semi-circular seats or notches 11—11 which are so positioned as to register with the alined apertures 5 and 7 in the head and handle respectively, and are adapted to bear against and to receive the transverse pin 6 in a manner to prevent their longitudinal movement upon the handle.

15 The handle is furthermore provided with the usual longitudinal wedge 13 extending from the outer end of the handle a distance substantially equal to the width of the head 1, said wedge having a central aperture 14 for the passage of the pin 6. The wedge is driven into the handle to spread the same apart and form a tight fit within the shield plates 8—8, which are thus forced into close engagement with the walls of the eye 3 of the head 1. It will be seen that after the several parts are assembled in the manner described, and the pin 6 driven home, the said parts are securely held together and may not become accidentally separated, the 20 pin being of a length to lie flush with the sides of the head 1 and of a diameter to tightly fit the several bores so as not to be jarred loose. If desired the pin may be upset at either or both ends to hold the same 25 in place.

In Figs. 6 and 7, there is illustrated a single edged ax 15 having one of the shields of the present invention applied thereto, said shield differing somewhat from that 30 already described, in that the notches 11 are dispensed with, and a suitable aperture or seat formed through the center of the U-shaped wings of the shield plate, for the reception of the pin 17, which further traverses an aperture in the wedge 18 and also apertures in the side walls of the ax 15, as in the first described form of the invention. In the single edged ax it is only necessary to use one of the shield plates, as the handle 35 will only be struck upon the edge next to the cutting edge of the head 15, whereas in the case of the double-edged ax, a pair of the shields is necessary.

From the foregoing it will be seen that a 40 simple, cheap and efficient shield or protector has been provided for use upon handles of axes, and other similar tools which, in use, are subjected to the force of striking blows and which are often split or broken 45 when, by accident, the handle of the tool is brought into contact with the article operated upon.

While both wedges and shields for axes are old, I am not aware that anyone has ever 50 produced the combination herein described,

in which the wedge, handle, and shield are all secured to the ax head by a single pin.

It will be noted that in both forms of the invention, the wedge is equal in width to the handle, so that when applied, the longitudinal edges of the wedge engage the inner face 70 of the shield plate or plates.

It has been proposed to use ax handle shields which are integral with the head. Such shields would add materially to the 75 cost of making the ax head and would require special shaping of the handle each time a new one is fitted. Ax handle shields separate from the head have been used, but when in position on the handle have been wholly 80 outside the eye of the head. The present invention is distinguishable from what others have done in this line in extending the ax shield into the eye of the ax, where it is held firmly in place without movement from the 85 head. The pin prevents movement of the shield which might cause an abrasion or chafing of the handle near where it enters the eye. Furthermore, the shield coöperates 90 with the wedge in holding the head firmly upon the handle.

What is claimed is—

1. The combination with an ax head or similar tool having an eye and a handle therefor, a metallic shield plate U-shaped in 95 cross section bent to conform to the shape of the handle and practically surrounding the same at the end where entering the eye, said plate fitting against the wall of the eye and extending across the plane of action 100 of the tool and projecting along the handle beyond the inner side of the head a sufficient distance to serve as a protection for that portion of the handle contiguous to the head, said plate having an equal thickness throughout and a width within the eye greater than the corresponding dimension without the eye, said handle having a transverse bore, said ax head also having a transverse bore, said shield plate having a transverse seat, a wedge adapted to be driven into the end of the handle where entering the eye of the ax head and having a transverse aperture adapted to register with the bores 110 in the handle and head and the seat in the shield, and a transverse pin of a size to fit the specified bores, aperture and seat to hold the parts together.

2. In combination with an ax head or similar tool having an eye, and a handle 120 therefor, a metallic shield plate substantially U-shaped in cross section bent to conform to the shape of the handle and substantially surrounding the same at the end where entering the eye, said plate fitting throughout 125 the wall of the eye from one end to the other across the plane of action of the tool and projecting along the handle beyond the inner side of the head a sufficient distance to serve as a protection for that portion of the 130

handle contiguous to the head, said handle having a transverse bore, said ax head also having a transverse bore, and said shield plate having a transverse seat, a wedge substantially equal in width to the width of the handle end entering the eye and adapted to be driven into said end with one of its longitudinal edges in substantial contact with the inner side of the shield plate, said wedge 5 being nearly equal in length to the length of the eye and having a transverse aperture adapted to register with said bores in the handle and head and said seat of the shield plate, and a pin of a size to fit the said 10 bores, said aperture and said seat and adapted to be driven therein to hold all the parts together.

3. In combination with an ax head or similar tool having an eye, and a handle 20 therefor, a metallic shield or protector composed of two plates substantially U-shaped in cross section bent to conform to the shape of the handle and to practically surround the same at the end thereof where entering 25 the eye, said plates fitting throughout the wall of the eye from one end to the other and projecting along the handle beyond the inner side of the head a sufficient distance to

serve as a protection for that portion of the handle contiguous to the head, said handle having a transverse bore, said ax head also having a transverse bore, and said shield plates having registering seats or notches, a wedge adapted to be driven into the end of the handle where entering the eye 30 of the ax head and having a length nearly equal to the length of the eye and having a width substantially equal to the width of the ax handle, whereby the longitudinal edges of the wedge are adapted to engage 35 the inner sides of the shield plates, said wedge having a transverse aperture which is adapted to register with said bores in the handle and head and said seats in the shield plates, and a transverse pin of a size to fit 40 said bores, aperture and seats and adapted to be driven therein to hold all of said parts together.

In testimony, that I claim the foregoing as my own, I have hereto affixed my signature in the presence of two witnesses.
